CARBURETOR FOR INTERNAL COMBUSTION ENGINES

Stéphane Surra, Chambery, France

Application February 14, 1935, Serial No. 6,492
In France March 19, 1934

3 Claims. (Cl. 261—41)

In ordinary carburetors the main jet disposed stationary in the admission inlet only gives its full delivery i. e. is situated in the zone of maximum suction when the butterfly valve or the like is fully opened.

For intermediary running positions its delivery is defective owing to the fact that the zone of suction is transferred to the level of the restrictions of the butterfly valve or the like which it follows and in which the jet is not disposed owing to its stationary position.

The improvements according to the present invention have chiefly for object to overcome this inconvenience.

For this purpose this carburetor comprises, apart from its slow running jet, a multiplicity of jets which come into action one after the other step by step, as the shutter (butterfly valve or the like) opens, but which, as soon as they come into action, are in a zone of maximum suction so operating at full delivery under the best conditions.

These jets which with full opening, are all in action, are calculated so that their total delivery corresponds with that of the single jet ordinarily used in present day carburetors and the respective delivery of each one of them is likewise calculated according to the degree of opening of the shutter according to which it respectively comes into action.

The invention also has for object numerous further features which will be readily understood by referring to complementary description which follows, reference being had to the accompanying drawings which, both the description and drawings, naturally are given solely by way of example, and refer to a carburetor comprising three main jets and a slow running jet.

In these drawings, Figures 1 and 2 are two views of a carburetor seen respectively in elevation and in section on the line 1—1 and 2—2 of Figure 3.

Fig. 3 is a plan view of the body, the butterfly valve or the like being shown in dotted lines fully opened, the cover and the air inlet tube being removed.

Fig. 4 is a corresponding side elevation of the jets, the valve body being removed.

Fig. 5 is a cross section of the air admission pipe taken on the line 5—5 of Fig. 2.

According to the invention this carburetor comprises a float chamber 2 to which the gasolene is admitted through the pipe 3 the constant level 55 of same being ensured as usual by a float 4.

The float chamber is in communication through pipes 26 with the jet chamber 6, 6', 6'' of the main jets 7, 7', 7'' of which there are three shown in the example.

These jets which have their outlets in the pipes 8, 8', 8'', in communication through the intermediary of a turnable valve body 9 with the flange 10 for connection to the manifold of the motor, have three holes 11 and are each disposed in passages 12, 12', 12'' within which air can enter through the channels of passages 13, 13', 13''.

The turnable valve body 9 which is mounted on ball races 14 is pierced through with an oval communication hole 15. Its rotation is effected by a hand lever 16 fast on its spindle 17.

The cover 18 maintains it in place.

The channels or pipes 8, 8', 8'' which have an internal diameter corresponding to the output of the jets 7, 7', 7'' are in communication with the atmosphere through a pipe 19.

This pipe is provided with a partition or wall 20 forming a communication chamber through the intermediary of a regulating shutter or baffle 21 actuated at 22, with a hot air arm pipe 23.

The slow running of the motor, turnable valve body being closed, is obtained by means of the jet 24, mounted on a jet chamber 25 in communication with the float chamber 2 by means of a passage 26.

This jet delivers into a superposed passage 27. Between them the air can enter at 30 and a hand adjustable screw threaded nut 28 permits of adjusting this air passage 30, the said screw threaded nut 28 being secured after adjustment by a lock nut 29.

A second air inlet at 13''' operates under the same conditions as do the parts 13, 13', 13'' on the jets 7, 7', 7''.

On the pipe 27 which has its outlet at the flange 40 10 beyond the valve body 9, is intercalated a needle valve 31 which can be adjusted by means of a nut 32 which can be secured in position by means of a lock nut 29'. The spindle of this needle valve which is actuated by a spring 33 45 bears on this nut through the intermediary of an eccentric lever 34 actuated at 41.

Finally a stirrup piece 35 oscillating at 36 and provided with an abutment bolt 37, ensures the tightness of the joint 39 for the float chamber 2, 50 which carries the whole of the jets with the body proper 38 of the carburetor.

To dismantle the jets 24, 7, 7', 7'' it is only necessary to loosen the plugs 40, 40', 40'', 40''' forming the ends of the jet chambers 25, 6, 6', 6''.

Thus the valve body 9 being actuated at the opening up of the carburetor, in the direction of the arrow, its pipe 15 first uncovers the jet 7 then the jet 7' and finally when fully opened the jet 7'', 5 these jets as soon as they are uncovered, giving their full delivery because they are disposed in the zone of maximum suction.

On the other hand, the air which has access to each one of these jets through the pipes 13, 10 13', 13'' and by the holes 11, energetically mixes the gasolene before it is drawn into the motor.

The delivery of each of these jets 7, 7', 7'' is adjustable by a needle or pointed screw 5 actuated by hand and the movement of which is 15 braked by a spring.

Similarly, each of the jet chambers 6, 6', 6'' fills with gasolene when the corresponding jet is not in action and so forms a reserve of spirit which enables rapid accelerations to be made.

20 In regard to the slow running jet 24, the entry of air to which is adjustable by hand by means of the nut 28 without necessitating any tool, it forms at the same time a compensating means for filling the vacuum which occurs at 25 the commencement of the opening of the valve body 9 before the jets 7, 7', and 7'' come into action.

This slow running adjustment may be manually regulated according to the external temperature 30 by means of the needle valve 31 which can be lifted temporarily when starting up by means of a lever 34 in order to completely uncover the passages 27 and 13''' and without the adjustment being altered.

35 The air inlet pipe 19 avoids the noise of the suction which occurs with ordinary carburetors and its wall 20 with adjustable shutter 21 allows the admission of hot air through the pipe 23 so giving a better output and facilitating starting up.

40 The dismantling of the float chamber 2 is simple and rapid and with it the whole of the jets and the jet chambers can be removed.

Finally as is obvious and as will have already 45 been seen, the invention is in no way limited to the single example of construction described above nor to that of its different parts but on the contrary it comprises all variations in construction comprising the application of similar means.

50 I claim:

1. A carburetor comprising in combination a pair of interfitting superposed sections, the lower section providing a float chamber and the upper 55 section providing a valve chamber substantially aligned with said float chamber, a plurality of independent upwardly extending carbureting chamber-providing bosses disposed radially on said float chamber section, jet tubes extending

upwardly in said bosses above the tops thereof and communicating with said respective carbureting chambers of said bosses, a series of air supply nipples carried by said upper section radially thereof and communicating with said valve chamber, each of said air supply nipples having a hole into which one of said jet tubes projects, a valve in said valve chamber and movable to serially establish communication between said nipples and valve chamber, and means for holding said interfitting carburetor sections assembled. 5

2. A carburetor comprising in combination a pair of interfitting superposed sections, the lower section providing a float chamber and the upper section providing a valve chamber substantially aligned with said float chamber, a plurality of independent upwardly extending carbureting chamber-providing bosses disposed radially on said float chamber section, jet tubes extending upwardly in said bosses above the tops thereof and communicating with said respective carbureting chambers of said bosses, a series of air supply nipples carried by said upper section radially thereof and communicating with said valve chamber, each of said air supply nipples having a hole into which one of said jet tubes projects, a valve in said valve chamber and movable to serially establish communication between said nipples and valve chamber, regulating valves for said respective jet tubes carried by said nipples, 30 and means for holding said interfitting carburetor sections assembled. 25

3. A carburetor comprising in combination a pair of interfitting superposed sections, the lower section providing a float chamber and the upper 35 section providing a valve chamber substantially aligned with said float chamber, a plurality of independent upwardly extending carbureting chamber-providing bosses disposed radially on said float chamber section, jet tubes extending 40 upwardly in said bosses above the tops thereof and communicating with said respective carbureting chambers of said bosses, a series of air supply nipples carried by said upper section radially thereof and communicating with said valve chamber, each of said air supply nipples having a hole into which one of said jet tubes projects, a valve in said valve chamber and movable to serially establish communication between said nipples and valve chamber, said jet tubes being spaced from 45 the walls of said bosses above said carbureting chambers thereof, and the upper ends of said bosses being spaced from said air inlet nipples of said upper section, said jet tubes having air inlet holes below the upper ends of said bosses 50 whereby to provide an auxiliary air inlet for each jet tube, and means for holding said interfitting carburetor sections assembled. 55

SURRA, STÉPHANE.
